CLAIM

The ornamental design for a multi-purpose sprayer, as shown and described.

DESCRIPTION

FIG. 1 is a perspective view of the multi-purpose sprayer showing my new design.

FIG. 2 is a front view thereof;

FIG. 3 is a back view thereof;

FIG. 4 is a top view thereof;

FIG. 5 is a bottom isometric view thereof;

FIG. 6 is a right side isometric view thereof; and,

FIG. 7 is a left side isometric view thereof.

The dashed broken lines depict portions of the multi-purpose sprayer that form no part of the claim.
